Attorney

UNITED STATES PATENT OFFICE.

WILLIAM A. SMITH, OF EASTON, PENNSYLVANIA, ASSIGNOR TO THE DENVER ROCK DRILL MANUFACTURING COMPANY, OF DENVER, COLORADO, A CORPORATION OF DELAWARE.

DRILLING APPARATUS.

1,345,271.

Specification of Letters Patent. Patented June 29, 1920.

Application filed April 6, 1918. Serial No. 227,003.

To all whom it may concern:

Be it known that I, WILLIAM A. SMITH, a citizen of the United States, residing at Easton, in the county of Northampton and State of Pennsylvania, have invented certain new and useful Improvements in Drilling Apparatus, of which the following is a specification.

The present invention relates to drilling apparatus, and more particularly to means for supplying cleansing fluid to the bore of a drill bit for delivery to the bottom of the drill hole to eject the cuttings.

The principal object is to provide simple and effective means of a novel character for supplying both gaseous and liquid cleansing fluid to the drill steel bore.

The preferred embodiment of the invention is illustrated in the accompanying drawings, wherein:—

Figure 1 is a longitudinal sectional view through the head end of a well known type of drilling apparatus.

Fig. 2 is a sectional view on the line 2—2 of Fig. 1.

Similar reference numerals designate corresponding parts in all the figures of the drawings.

In the embodiment illustrated, a portion 30 of the usual barrel is illustrated at 3, the piston chamber 4 being closed by a head 5 fitted to the front end of said barrel. The chuck is shown at 6, and interposed between the chuck and head is a collar 7. The chuck 35 6 includes a bushing 8 for the reception of the rear end of the drill steel, a portion of which is illustrated at 9. This steel, as usual, has a bore 10 longitudinally therethrough for directing cleansing fluid to the bottom of the drill hole.

The collar 7 is provided with a nipple having a liquid inlet 11 terminating in a relatively small port 12. The joint between the collar 7 and the head 5 is such as to provide an annular groove or passageway 13 that is in communication with one side of the inlet 11 through a port 14. The piston chamber 4 is in communication with the passageway 13 by means of a port 15, said port having an enlargement forming an internal valve seat 16. Coöperating with this seat, is a ball valve 17 normally held closed by a coiled spring 18 bearing against it. The outer end of said spring bears against

a washer 19 that abuts against the rear end 55 of the collar 7.

Slidably mounted in the collar 7 and the head, is a tappet 20 having a passageway 21 that communicates with the port 12 and with the bore 10 of a drill steel placed in 60 the chuck 6.

With this arrangement, it will be evident that if a water tube is connected to the inlet 11, water through said tube will obviously pass through the port 12 and passageway 65 21 to the bore 10 of the drill steel. Fluid under pressure that enters the front end of the piston chamber 4 will pass through the port 15, and unseating the valve 17, will find its way through the passageway 13 and 70 port 14 to the inlet 11, so that it will also be directed to the bore of the drill steel. Any back pressure of the fluid will, however, be prevented by the ball 17 seating itself.

From the foregoing, it is thought that the 75 construction, operation and many advantages of the herein described invention will be apparent to those skilled in the art, without further description, and it will be understood that various changes in the size, 80 shape, proportion, and minor details of construction, may be resorted to without departing from the spirit or sacrificing any of the advantages of the invention.

Having thus fully described my invention, 85 what I claim as new, and desire to secure by Letters Patent, is:—

1. In drilling apparatus of the character set forth, the combination with a barrel and a head therefor, of a chuck, a tappet holding collar interposed between the head and chuck and having a cleansing fluid inlet, a tappet in the collar having a cleansing fluid port communicating with the inlet and delivering to the bore of a steel placed in the 95 chuck, and a passageway in the head communicating with the barrel and the inlet for delivering fluid from the former to the latter.

2. In drilling apparatus of the character 100 set forth, the combination with a barrel and a head therefor, of a chuck, a tappet holding collar interposed between the head and chuck and having a fluid cleansing inlet, the juncture of the head and collar forming a 105 fluid passageway, a port in the head affording communication between the barrel and passageway, a port in the collar affording

communication between the passageway and inlet, and a tappet in the collar having a cleansing fluid port communicating with the inlet and delivering to the bore of a steel placed in the chuck.

3. In drilling apparatus of the character set forth, the combination with a barrel and a head therefor, of a chuck, a tappet holding collar interposed between the head and chuck and having a cleansing fluid inlet, a tappet in the collar having a cleansing fluid port communicating with the inlet and delivering to the bore of a steel placed in the chuck, a passageway in the head communicating with the barrel and the inlet for delivering fluid from the former to the latter, and a check valve for preventing the flow of fluid from the inlet to the barrel and preventing the flow of the fluid from the barrel to the inlet.

4. In drilling apparatus of the character set forth, the combination with a barrel and a head therefor, of a chuck, a tappet holding collar interposed between the head and chuck and having a cleansing fluid inlet, the juncture of the head and collar forming a fluid passageway, a port in the head affording communication between the barrel and passageway, a port in the collar affording communication between the passageway and inlet, a tappet in the collar having a

cleansing fluid port communicating with the inlet and delivering to the bore of a steel placed in the chuck, and a check valve in the head for permitting the flow of fluid through the port from the barrel and preventing the flow of fluid through the port to the barrel.

5. In drilling apparatus of the character set forth, the combination with a barrel and a head therefor, of a chuck, a collar interposed between the chuck and head, the joint between the collar and head forming an annular passageway, said collar having a fluid inlet, a port connecting the annular passageway and the inlet, a port connecting the barrel and passageway, said port having an internal valve seat, a valve co-operating with the seat, a spring operating against the valve, said valve and spring being held in place by the collar, and a tappet slidable in the collar and head and having a passageway communicating with the fluid inlet for delivering fluid to the bore of a drill steel placed in the chuck.

In testimony whereof I affix my signature in the presence of two witnesses.

WILLIAM A. SMITH.
